UNITED STATES PATENT OFFICE.

HARRY F. HITNER, OF WILKINSBURG, PENNSYLVANIA.

ELECTRIC-LAMP SOCKET.

1,380,063.

Specification of Letters Patent. Patented May 31, 1921.

Application filed December 1, 1919. Serial No. 341,704.

To all whom it may concern:

Be it known that I, HARRY F. HITNER, a citizen of the United States, and a resident of Wilkinsburg, in the county of Allegheny and State of Pennsylvania, have made a new and useful Invention in Electric-Lamp Sockets, of which the following is a specification.

The invention relates to electric lamp sockets. It has for its principal object the provision of a cheap simple socket which can be readily made from glass, porcelain, vulcanite or other insulation material, which requires no screws, in which the connections between the leading in wires and terminals are relieved of all the strain of supporting the socket, and in which the wires can be attached and locked securely in position in a most expeditious manner and without the use of tools. Certain embodiments of the invention are illustrated in the accompanying drawings, wherein:

Figure 1 is a vertical section through the socket with the parts in the position occupied just before screwing in the cap. Fig. 2 is a plan view of the body portion of the device. Fig. 3 is a partial vertical section through a modified construction, and Fig. 4 is a plan view of the construction of Fig. 3. Referring to the drawings, 1 is the body or socket portion of the device provided with the partition 2, having the slots 3 and 4. This body portion may be made of any desired insulating material, such as glass, porcelain or vulcanite, glass being preferred because of its cheapness. The front portion of the socket is threaded so as to receive the metal contact sleeve 5, while the rear portion is threaded as indicated at 6 to receive the cap 7. This cap is provided with a flange portion 8 adapted to be threaded into the body portion and is also provided with an opening 9 for the passage of the leading in wires 10 and 11. This cap portion is also preferably made of the same material as the body or socket portion and is threaded at the opening 9 so as to be adapted to be secured to a pipe connection when the socket is desired to be used in this way.

The contact sleeve 5 is provided with a terminal 12 in the form of a strip which has a bent over end back of the partition 2, such bent over end being provided with slots 13, as

indicated in Fig. 2, to provide for the more 55 secure attachment of the leading in wire. A second lamp contact member 14 is provided at the center of the partition 2, such member being provided with a terminal 15, having a bent over notched end 16 (Fig. 2) 60 similar to that of the other terminal. The sleeve 5 may be molded in the material of the socket in case such material is vulcanized, but if the material of the socket is glass, such sleeve is preferably screwed in 65 after the formation of the socket. In so assembling the two parts the terminal strip 12 is bent down inside the shell with its free end directed inwardly. After the shell is screwed to position, the end of the strip 12 70 is pressed through the slot 3 and bent over as illustrated.

In order to attach the leading in wires to the binding terminals 12 and 15, loops are formed on the ends of the wire which are 75 hooked around the ends of the terminals and set in the recess 13. This gives a temporary attachment between the wires and terminals and prevents the detachment thereof while the cap is being screwed in or in case such 80 cap should become accidentally loosened after being screwed in. When the cap is screwed in, the end of the flange 8 engages the connections between the leading in wires and the binding terminals and clamps such 85 connections, the cap being screwed down to such an extent that the bent over ends are flattened down, thus clamping the wires between the opposing surfaces of the binding terminals, and also very securely clamping 90 such wires to the socket itself. The bent over ends are preferably of spring material so that when the cap is screwed firmly into position, the bent over ends apply a continuous yielding pressure to the cap and tend 95 to prevent the unscrewing of the cap, the effect being similar to that of the well known spring washer nut lock. In order to still further guard against the unscrewing of the cap, the lower edge of the flange 8 may be 100 made slightly corrugated, as indicated at 17, so that when the cap is screwed tightly into position an increased resistance against unscrewing is afforded. These corrugations must be made relatively slight in order not 105 to give too much twisting upon the binding terminals when the cap is screwed into position.

Figs. 3 and 4 illustrate a construction which is slightly modified with respect to the binding terminal 18. The slot 19 for this terminal is placed closer to the side wall 20 of the socket than in the construction of Fig. 1, and this calls for a reverse band 21 upon the terminal. In this form of construction the terminals, instead of being notched at their ends, are provided with perforations 22 for connection with the leading in wires.

It will be seen that when the cap is screwed into position and the leading in wires clamped, all strain is removed from the connection between the leading in wires 15 and the terminals, so that the danger of the leading in wires becoming detached is reduced. The construction also avoids the inconvenience and expense incident to the use of binding screws for the terminals. It is a 20 very easy matter to loop the wires over the terminals or to pass them through perforations in such terminals, and this connection is then made very secure when the cap is screwed into position. The 25 making of the terminals of spring material not only provides the locking feature for the cap, tending to prevent its unscrewing, but such feature permits the return of the ends to their original positions when the cap is unscrewed, which 30 would not be the case if non-spring material were used, and the ends were flattened down permanently by the pressure of the cap. Many variations in the details of the 35 construction may obviously be made without departing from the invention, which contemplates broadly the use of the cap to clamp the leading in wires and terminals and their connections and also to clamp such wires to 40 the socket. A great variety of connections may be made between the wires and terminals and the cap may be secured in position in a variety of ways although the screw connection is preferred.

What I claim is:

1. In combination in a device of the class described, an insulating lamp socket, a plug or cap of insulating material threaded upon its exterior and screwing into the rear end of the socket, and binding terminals in the 50 socket adapted to be connected with the ends of leading in wires and positioned opposite the end of the cap so that when the cap is screwed down into the socket the end thereof engages the connections between the wires 55 and terminals.

2. In combination in a device of the class described, an insulating lamp socket, a one-piece cap in the form of an annular ring of insulating material screw threaded into the 60 rear end of the socket, and binding terminals in the socket adapted to be connected with leading in wires and located opposite the edge of the cap so that when such cap is screwed down into the socket the edge thereof engages and clamps the connections between the wires and terminals.

3. In combination in a socket, a body portion of insulating material and comprising a cylindrical member with a transverse partition portion intermediate its ends, lamp contact members forward of the partition, wire terminals extending from said contact members to the rear of the partition and provided with end portions for engaging the 75 ends of leading in wires, and a plug of insulating material threaded upon its exterior and screwing into the socket, the front end of such plug being in alignment with the connections between the terminals and leading in wires, so that when the plug is 80 screwed into position it clamps the said connections against said partition.

In testimony whereof, I have hereunto 85 subscribed my name this 28th day of Nov., 1919.

HARRY F. HITNER
